UNITED STATES PATENT OFFICE

JOHN DEEBLE, OF SOUTHINGTON, CONNECTICUT, ASSIGNOR OF ONE-HALF
TO JULIUS B. SAVAGE, OF SAME PLACE.

OX-SHOE.

SPECIFICATION forming part of Letters Patent No. 338,937, dated March 30, 1886.

Application filed February 19, 1886. Serial No. 192,589. (No model.)

To all whom it may concern:

Be it known that I, JOHN DEEBLE, a citizen of the United States, residing at Southington, in the county of Hartford and State of Connecticut, have invented certain new and useful Improvements in Ox-Shoes, of which the following is a specification.

My invention relates to improvements in ox-shoes; and the main object of my invention is to enable the shoe to be more securely attached to the foot.

In the accompanying drawings, Figure 1 is a reverse plan view of a pair of my ox-shoes, and Fig. 2 is a side elevation of one of said shoes showing the outer edge.

The main portion of the shoe may be of any ordinary construction, the same being provided with heel-calks *a* and toe-calks *b*, as shown. In front of the toe-calks *b* I form an extension, *c*, in which is a nail-hole, *d*, so that one nail may be driven into each part of the divided hoof at a point forward of the toe-calk *b*. It is well known that the hoofs of oxen are the hardest and the horny shell the thickest toward the toe, and therefore a nail has more holding power at the points of the hoof than elsewhere. Furthermore, when a shoe catches on some object near the toe and is pulled upon

as the animal steps along, the nearer the nails are placed to the point of the toe the more 35 they will hold, even if the hoof were no harder at that point. The extension *c* also furnishes available stock from which the blacksmith can form the holding "scarf" or lip *e*. This he can do by turning down a little of the metal 35 from the inner edge of the extension just forward of the calk.

I am aware that ox-shoes have been made with three or more calks and with nail-holes forward of the middle calks, and I hereby dis- 40 claim the same. In my shoe the toe-calks are not drawn backward toward the middle of the shoe, but said calks occupy the same position as the toe-calks of ordinary shoes, and the extension *c* covers a part of the hoof, which is 45 left bare by the ordinary shoe.

I claim as my invention—

The herein-described ox-shoe having the extension *c* forward of the toe-calk, substantially as described, and for the purpose speci- 50 fied.

JOHN DEEBLE.
